UNITED STATES PATENT OFFICE.

ALONZO E. NELSON, OF BROCKTON, MASSACHUSETTS.

COMBINATION-TOOL.

SPECIFICATION forming part of Letters Patent No. 280,849, dated July 10, 1883.

Application filed December 23, 1882. (No model.)

To all whom it may concern:

Be it known that I, ALONZO E. NELSON, of Brockton, in the county of Plymouth, State of Massachusetts, have invented a certain new and useful Improvement in Tool-Stocks, of which the following is a description sufficiently full, clear, and exact to enable any person skilled in the art or science to which said invention appertains to make and use the same, reference 10 being had to the accompanying drawings, forming a part of this specification, in which—

Figure 1 is an isometrical perspective view, showing the calipers and screw-driver opened and the level in a vertical position; Fig. 2, a 15 vertical transverse section, showing the gears; Fig. 3, a plan view of the gears; Figs. 4 and 5, sectional views for reference; Fig. 6, a view of the rule detached; Fig. 7, a side elevation; Fig. 8, a sectional view, showing the gears, 20 and also the coupling rod or clutch; Fig. 9, a plan view, showing the jaws of the chuck closed; Fig. 10, a view of the wrench; Fig. 11, a plan view, showing the jaws of the chuck opened or extended; Fig. 12, a view of some 25 of the smaller parts detached, and Fig. 13 a view of the rule arranged as a centering-gage.

Like letters of reference indicate corresponding parts in the different figures of the drawings.

30 This invention relates to tool-stocks adapted to receive various tools or implements which may be detached or used independent of the common stock or handle, said stock being provided with a chuck, as hereinafter described.

35 In the drawings, A represents the body or stock, which is provided with four radial and vertically-arranged flanges, B C D E, designed to receive and hold, respectively, the calipers G, level t, screw-driver J, and rule K, the calipers, rule, and screw-driver being secured in 40 position and rendered detachable by the thumb-screws m, and the flange E, provided with the V-shaped notch 45. The rule is provided at its upper end with two laterally-projecting short arms, a b, forming the slot d, for receiving the screw by which it is secured in the body A, rendering it adapted for use as a wrench for certain kinds of light work. It may also be provided with a scale of inches and fractional parts thereof, if desired, and also used 45 as a centering-tool by securing it in a horizon-

tal position with its lower edge at the center of the notch 45.

The calipers are adapted for use both as calipers and dividers, the arms z z being pointed, 55 and provided at one end with the lateral projections h h and at their centers with the slots i i. They may also be used as surface-gages by securing one or both of the arms z z in a vertical position, with their points at any desired height from the bottom of the body. Two arms, f f, are conjointly pivoted at G in the body A, these arms being provided at their outer ends with sliding pivots j j, working in the slots i, thereby enabling the arms z to be 60 reversed on the arms f, and used, as occasion may require, either as dividers or calipers or as a surface-gage.

The level or glass t in the flange C is arranged vertically, but is adapted for use either vertically or horizontally, as desired, or according to the position in which the body A is placed.

The screw-driver J may be readily detached, if desired; but the body A serves in most instances as a proper handle for the same, as it 75 does for the calipers and square.

Journaled vertically in the center of the body there is a rod, L, provided at its lower end with the horizontally-arranged miter-gear M, which intermeshes with four corresponding 80 vertically-arranged miter-gears, x, mounted on the inner ends of the horizontal screws v. These screws each carry a chuck-jaw, q, as best seen in Figs. 8, 9, and 11, the screws and jaws being arranged to work in proper bearings and ways provided for that purpose.

The body A is fitted with a nut, N, which is screwed into its upper end and bored or chambered vertically to receive the upper end of the coupling-rod O, this rod being detachably 90 jointed to the rod L, as shown at l. The rod O is fitted with a coiled spring, n, which acts expansively on the boss w to keep the rods O and L interlocked. The upper end, P, of the rod O is squared and fits a corresponding hole 95 in the loose boss Q, which is used for turning the rod O, and is covered with a cap, F, attached to the screw p and turning with the rod.

In the use of my improvement the chuck may be operated through the rod L, gears M 100 x, and screws v by means of the boss Q, which, when turned to the right or left, will cause the

jaws *q* to close upon and hold any article placed between them, or open and release the same, as the case may be, in a manner which will be readily obvious without a more explicit description.

5 In case the chuck is employed for turning on or off nuts, or on work where a heavy strain has to be brought upon the body *A*, the wrench *w* may be used, the inwardly-projecting studs 20 being adapted to fit the notches 25, formed in the periphery of the horizontal flange *Y* on the upper part of the body. The wrench is also provided with a hexagonal hole, *T*, at its outer end for turning the nut *N*.

10 15 A screw-eye, 15, for attaching a plumb-cord, 18, is provided at the lower end of the body *A*, which may be detached when the plumb is not in use.

20 The methods in which the various implements embodied in the tool may be used to advantage will readily suggest themselves, and it is therefore deemed unnecessary to give them more fully.

25 Having thus explained my invention, what I claim is—

30 1. A tool-stock provided with a chuck at one end and with means for operating the same, said stock being constructed with longitudinal ribs provided with slots adapted to receive various tools, substantially as described.

35 2. A tool stock or chuck consisting of a tubular body provided with radially-sliding jaws at one end, a rotary rod within said body, provided with a slot at its upper end, mechanism connecting said rod with said jaws, a

shouldered coupling-rod provided with a tongue adapted to project into said slot for coupling said rods, a spring for forcing said parts into connection with each other, and means for rotating said coupling-rod, substantially as described.

3. A tool stock or chuck consisting of the tubular body *A*, having the nut *N* at one end, the radially-sliding jaws *q* at its opposite end, the screws *v*, provided with the miter-gears *x* 45 at their inner ends and working in said jaws, the rotary rod *L*, slotted at one end, and provided at its opposite end with the miter-gear *M*, adapted to intermesh with the gears *x*, the coupling-rod *O*, provided with a tongue, *l*, 50 spring *n*, and boss *Q*, all constructed, combined, and arranged to operate substantially as described.

4. A tool stock or chuck consisting of the tubular body *A*, having the chambered nut *N* 55 at its upper end and the radially-sliding jaws *q* at its lower end, the screws *v*, provided with the miter-gears *x* at their inner ends and working in said jaws, the rotary rod *L*, slotted at one end, and provided at its opposite end with the miter-gear *M*, adapted to intermesh with the gears *x*, the squared coupling-rod *O*, provided with a tongue, *l*, the expansile spring *n*, 60 adapted to hold said rods in contact, the boss *Q* for turning the rods, and the cap *F*, substantially as described.

ALONZO E. NELSON.
